UNITED STATES PATENT OFFICE

WILLIAM C. GRAY, OF RICHMOND, VIRGINIA, ASSIGNOR OF ONE-HALF TO J. E. MOSS

DESIGN FOR A DIRECTION SIGNAL FOR AUTOMOBILES

Application filed January 30, 1929. Serial No. 29,841. Term of patent 7 years.

To all whom it may concern:

Be it known that I, WILLIAM C. GRAY, a citizen of the United States, residing in Richmond, in the county of Henrico and State of Virginia, have invented a new, original, and ornamental Design for a Direction Signal for Automobiles, of which the following is a specification, reference being had to the accompanying drawing, forming part thereof, in which:

Figure 1 is a front elevation of the direction signal, showing my new design;

Figure 2 is a top plan view of the same, and Figure 3 is an end elevation of the signal light casing.

I claim:

The ornamental design for a direction signal for automobiles, as shown.

Signed at Washington, in the District of Columbia, this 22nd day of January, 1929.

WILLIAM C. GRAY.
